Application March 29, 1934, Serial No. 51,212

Term of patent 3½ years

To all whom it may concern:

Be it known that I, WILLIAM WILLHEIM, a citizen of the United States of America, residing at 115 Central Park West, in the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which my new design is applied except for the

portion between the break lines which is similar to that on either side thereof. The dot and dash lines on the drawing outline substantially the design unit which unit is repeated in regular succession as indicated by the extensions beyond the unit boundaries.

I claim:

The ornamental design for a textile fabric or similar article as shown and described.

In testimony whereof I have signed this specification.

WILLIAM WILLHEIM.
